ABSTRACT OF THE DISCLOSURE

Method of and apparatus for maintaining pre-cooled goods (for example, meat) during storage in a chamber at a temperature substantially the same as the average initial post-storage temperature of the goods. The method comprises first sensing the average air temperature near the floor of the storage chamber at a predetermined time after loading, then sensing continuously the average air temperature near the roof of the chamber, and refrigerating the chamber responsively to reduce the difference between the two sensed temperatures.

The method and apparatus according to the invention have been devised to meet the minimum refrigeration requirements for the successful storage of pre-cooled goods during their bulk transport. In general, the invention is described hereinafter with respect to the storage of goods in refrigerator railway carriages, but it will be understood that this particular application of the invention is described by way of illustration only.

After loading into a refrigerator railway carriage, the average temperature of a cargo of goods is not usually known, nor can it be readily measured. Factors which have a bearing on this average post-loading temperature are numerous and include: storage time and stacking methods used in a previous cool-room, refrigeration capacity of that cool-room, and conditions prevailing during transfer from cool-room to railway carriage. Thus, in the case of pre-cooled meat, chilling in a cool-room may have lowered the surface temperature of the meat to about 36° F., but the average temperature after loading into a refrigerator railway carriage may be as high as about 45° F.

According to refrigeration procedures currently practiced, the temperature control mechanism in the railway carriage is set to provide an arbitrarily selected temperature which may bear little relation to the average temperature of the cargo immediately after loading. If the arbitrarily selected temperature is much lower than this average temperature, a considerable and unnecessary strain is imposed on the refrigerating mechanism.

This known method is also subject to an additional disadvantage in that it involves the possibility of error on the part of the operator who is required to set the temperature control mechanism. In the case of pre-cooled meat, for example, the arbitrarily selected temperature may be 38° F., but the operator may inadvertently set the temperature at, say, 36° F. When refrigeration is achieved directly by spraying liquid carbon dioxide or liquid nitrogen on the cargo from the roof of the carriage, a total of about 150 lb. of refrigerant may be expended in reducing the temperature of an average load of chilled meat by 1 Fahrenheit degree. It can be seen therefore that errors in the selection of an appropriate storage temperature can be magnified by errors on the part of the operator, thus resulting in an appreciable overall wastage of refrigerant.

It is an object of the present invention to overcome

2

these disadvantages by providing a method of refrigeration designed to maintain automatically during storage substantially the average initial post-storage temperature of the pre-cooled goods.

- 5 The invention is based on the following premises:
(i) Pre-cooled goods are delivered to a storage chamber—say, a railway refrigerator carriage—at an average temperature lying in a temperature range considered to be optimum for the goods in question;
10 (ii) Depending on whether the air temperature in the carriage is initially greater than or less than the temperature of the cargo, the average temperature detected near the floor of the carriage will decrease or increase gradually after loading until it reaches a terminal value approximating the average initial post-storage temperature of the goods;
15 (iii) The period of time needed for this terminal condition to be reached can be predicted reliably from reference experiments in which the rate of temperature change is recorded for loading with goods of the given kind;
20 (iv) After the terminal condition has been reached, the minimum refrigeration requirements for storage during transport are satisfied if the carriage is then refrigerated to such an extent that the average temperature detected near the roof of the carriage is lowered towards the detected terminal value of the average temperature near the floor.
- Broadly, the invention provides a method of maintaining pre-cooled goods during storage at substantially the average initial post-storage temperature of said goods, said method comprising: loading a storage chamber with said goods; sealing the chamber; sensing continuously a first average air temperature towards the floor of the chamber during a predetermined first period of time; sensing continuously a second average air temperature towards the roof of the chamber during a subsequent second period of time; comparing continuously during said second period of time said second sensed average air temperature with the terminal value of said first sensed average air temperature, and refrigerating the chamber responsively to reduce the difference therebetween.
- The invention also provides apparatus for performing the defined method, said apparatus being adapted for installation in association with a storage chamber and comprising: a refrigerating control mechanism; first means for sensing continuously a first average air temperature towards the floor of the chamber during a predetermined first period of time and for supplying simultaneously said refrigerating control mechanism with a first temperature signal continuously indicative of said first sensed average air temperature; second means for sensing continuously a second average air temperature towards the roof of the chamber during a subsequent second period of time and for supplying simultaneously said refrigerating control mechanism with a second temperature signal continuously indicative of said second sensed average air temperature; a timing device for actuating said first temperature sensing means during said predetermined first period of time and for then actuating said second temperature sensing means; comparator means included in said refrigerating control mechanism for comparing continuously said second temperature signal with the terminal value of said first temperature signal; refrigerating means associated with said comparator means for refrigerating the chamber responsively to reduce the difference between said second temperature signal and the terminal value of said first temperature signal.

According to a preferred embodiment of the invention, the first and second temperature sensing means are adapted for pneumatic actuation by the timing device and the timing device is itself pneumatically operated.

In this embodiment, the timing device comprises: a gas storage reservoir linked by first pipe means to a source of compressed gas; said first pipe means including a diaphragm-operated valve for controlling gas flow from said source to said reservoir; means for effecting the closure of said diaphragm-operated valve when a pre-selected high pressure has been attained in said reservoir, said closure means comprising second pipe means for enabling closure-effecting communication between said reservoir and the diaphragm of said diaphragm-operated valve, said second pipe means including a non-return valve openable when said pre-selected high pressure has been attained in said reservoir; venting means for effecting the re-opening as required of said diaphragm-operated valve, said venting means being provided in the second pipe means between said non-return valve and the diaphragm of said diaphragm-operated valve and being adapted on actuation to reduce the pressure on said diaphragm; third pipe means linking said reservoir communicatively with the actuating mechanisms of said first and second temperature sensing means; bleeding means associated with said reservoir for enabling gas to escape therefrom at a controlled rate whereby to reduce the pressure therein from said pre-selected high value towards and below a preselected low value.

Conveniently, the actuating mechanism of one of the temperature sensing means (say, the first temperature sensing means) is adapted to operate when the pressure in the reservoir is in excess of this preselected low value, and the actuating mechanism of the other (second) temperature sensing means is adapted to operate when the pressure in the reservoir is less than the preselected low value.

The first and second temperature sensing means are hereinafter referred to as "floor" and "roof" temperature sensing means, respectively.

The functioning of the timing device will be explained more fully in the description relating to the annexed drawing. It can be seen, however, that the passage of gas from the source to the reservoir results in an increasing pressure therein, firstly until a value is reached at which the floor temperature sensing means is actuated, and secondly until a maximum value is reached at which the inflow of gas to the reservoir is terminated. This maximum pressure exceeds the low pressure at which the roof temperature sensing means is adapted to be actuated, but progressive loss of gas to atmosphere via the bleeding mechanism ensures that the pressure in the reservoir returns slowly to a value below which actuation occurs. The bleeding mechanism can be adjusted if necessary to delay actuation of the roof temperature sensing means to a variable extent, the period of delay being predetermined to suit the requirements of the cargo in question.

Provision of the described venting means in the timing device enables it to be returned to its initial condition when the required storage period is at an end.

The required degree of refrigeration can be effected by making use of any suitable refrigeration system, by way of illustration: "compression," "absorption," or "expendable liquefied gas" refrigeration systems.

An "expendable liquefied gas" refrigeration system is employed in the embodiment of the invention now to be described. According to this system, refrigeration is effected by (a) vapourizing a suitable liquefied gas in a heat exchanger within the storage chamber (indirect cooling) prior to discharging to atmosphere, or by (b) vapourizing a suitable liquefied gas in a heat exchanger as in (a), and then spraying the vapourized gas at low temperature into the storage chamber (direct cooling).

It will be appreciated that technique (b) is not favoured when the cargo comprises goods (e.g., chilled meat) which are affected detrimentally by an atmosphere depleted in oxygen; however, in technique (a) the discharge site can be arranged outside the storage chamber, in which

case the atmosphere within the chamber does not become depleted in oxygen.

5 Liquid nitrogen and liquid carbon dioxide both exemplify suitable gases for use in an "expendable liquefied gas" refrigeration system. Liquid nitrogen has generally been favoured for industrial refrigeration purposes, however, in the embodiment of the invention now to be described, liquid carbon dioxide is both the refrigerant and the source of gas for operating the (pneumatic) timing device.

10 The drawing shows schematically a system comprising apparatus for effecting minimum refrigeration according to the invention.

This system has been designed for installation in association with a railway refrigerator carriage (not shown), and consists of a combination of parts including: a vessel 1 for storing liquid carbon dioxide refrigerant; means consisting of a temperature sensing element 29 for sensing the average air temperature towards the floor of the chamber; means consisting of a temperature sensing element 36 for sensing the average air temperature towards the roof of the chamber; a refrigerating control mechanism comprising a pneumatic temperature transmitter 30 and a pneumatic temperature controller 35; a pneumatic timing device comprising a reservoir 20 for gaseous carbon dioxide and a constant bleed mechanism 21; refrigerating means selected as hereinafter explained from the group consisting of heat exchanger cooling means 38 and direct spray cooling means 39; selector valve 37 for selecting the desired refrigerating means; and master control valve 16 for isolating as required the entire control system from the vessel storing liquid carbon dioxide.

Summarised operation

35 The refrigerant supply vessel having been filled with liquid carbon dioxide and a cargo having been loaded into the storage chamber, the operator switches on the refrigeration control system by adjusting the master control valve 16, and selects the desired refrigerating means by adjusting selector valve 37. No further adjustments are necessary.

40 The pneumatic timing device now automatically measures a predetermined period of time during which the pneumatic temperature controller 35 is supplied via pneumatic temperature transmitter 30 with a pressure signal from floor temperature sensing element 29.

45 Subsequent to this measured period, the pneumatic temperature controller is supplied instead with a pressure signal from roof temperature sensing element 36. A comparison is then continuously made by the temperature controller between the terminal value of the sensed temperature near the floor with the prevailing value of the sensed temperature near the roof, and the refrigerating means is brought into action as required to reduce the difference between the two temperatures to zero. Other parts included in the system are discussed below in relation to various operational aspects.

Refrigerant supply

50 Liquid carbon dioxide, at a pressure of about 100 p.s.i.g. and a temperature of about -51° F., is supplied to vacuum insulated vessel 1 from liquid filling line 2 coupled to the inner pipe of a twin concentric feeding hose 3. The liquid is passed through strainer 4 and the supply is controlled by manually operated valve 5.

55 Gas displaced from the vessel is returned by gas line 6 to the manually operated valve 5 and thence to the annular space between the inner and outer pipes of the feeding hose. When the filling operation is completed, liquid carbon dioxide begins to return by the gas line to the feeding hose, and the manually operated valve 5 is then shut. Confirmation that this stage has been reached is obtained readily by opening try-cock 7 and testing for the presence therein of liquid carbon dioxide.

60 During those periods when refrigeration is not required

in the storage chamber, the refrigerant supply system is isolated from the rest of the apparatus and dangerous pressures are liable to be generated therein. To counter this possibility, the gas-containing section of vessel 1 is attached via heating coil 8 to a bleed valve 9 designed to open at pressures exceeding, say 105 p.s.i.g.

Communication between the refrigerant supply vessel and the refrigerating means occurs via ball valve 10, strainer 11 and non-return valve 12 in liquid supply line 13.

Communication between the refrigerant supply vessel and the refrigerating control system occurs by way of liquid filling line 2 through heating coil 14, strainer 15 and master control valve 16.

Manual adjustments

The refrigerant supply vessel having been filled with liquid carbon dioxide and a cargo having been loaded into the storage chamber, the operator switches on the refrigerating control system by adjusting the master control valve 16, and selects the desired refrigerating means by adjusting selector valve 37. The system is now under automatic control and no further adjustments are necessary.

When communication is effected between the refrigerant supply vessel and the refrigerating control system, a small quantity of liquid carbon dioxide is vapourized in the heating coil 14. The gas is then transmitted (at about 100 p.s.i.g.) by pipe line 17 towards the refrigerating control mechanism, and by pipe line 18 towards the pneumatic timing device.

Pneumatic timing

A diaphragm-operated valve 19, included in pipe line 18, is open at the start of the operation. Gas from pipe line 18 can therefore flow through this valve into reservoir 20 and its associated piping.

The reservoir communicates with a gas bleeding mechanism 21 and with the diaphragms of diaphragm-operated valves 22 and 23. A pipe line 24, 25, including non-return valve 26, is provided to enable delayed communication between the reservoir and the diaphragm of diaphragm-operated valve 19.

When the pressure in the reservoir builds up to 3 p.s.i.g., the arrangement is such that diaphragm-operated valve 22 is closed and diaphragm-operated valve 23 is opened. This actuation marks the beginning of a timed interval (referred to above as the predetermined first period of time).

Non-return valve 26 is adapted to be opened when the pressure in the reservoir builds up to 60 p.s.i.g., and diaphragm-operated valve 19 is adapted to be closed when pressure on its diaphragm exceeds 20 p.s.i.g. Accordingly, a stage is soon reached at which gas is admitted from the non-return valve to the diaphragm of diaphragm-operated valve 19. Closure of this valve is thereby effected and further supply of gas to the reservoir is then prevented. Pressure in the reservoir now returns gradually to normal by virtue of continuous loss of gas from bleeding mechanism 21. In the preferred embodiment shown in the drawing, gas passing through non-return valve 26 is admitted additionally to the diaphragm of another diaphragm-operated valve 27. The latter valve is included in a pipe line 28 interconnecting pipe line 18 and section 25 of pipe line 24, 25, and is adapted to be opened when pressure on its diaphragm exceeds 3 p.s.i.g. Accordingly, when gas at a pressure of about 60 p.s.i.g. passes from non-return valve 26 to the diaphragm of diaphragm-operated valve 27, the latter valve is opened and communication is effected between gas line 18 and the diaphragm of diaphragm-operated valve 19. Since the gas in gas line 18 is at about 100 p.s.i.g., it can be ensured by this arrangement that diaphragm-operated valve 19 will stay closed after the pressure in reservoir 20 has returned to normal. (If this refinement is omitted, the

possible development of minute leaks in the system could lead to the re-opening of the diaphragm-operated valve 19 as the pressure in the reservoir returns to normal.) As will be explained hereinafter, diaphragm-operated valve 27 and pipe line 28 also constitute venting means by which the pressure acting on the diaphragm of diaphragm-operated valve 19 can subsequently be released.

Diaphragm-operated valves 22 and 23 are again actuated when the pressure in reservoir 20 is reduced to 3 p.s.i.g., valve 22 now opening and valve 23 now closing. The interval between the two actuations of these valves is a constant determined essentially by the dimensions of the reservoir 20, the maximum pressure attained therein, and the orifice characteristics of bleeding mechanism 21.

Temperature sensing and control

A temperature sensing element 29 is mounted near the floor of the storage chamber. This element consists of a long capillary-type device adapted to supply pneumatic temperature transmitter 30 with a pressure signal whose magnitude depends on the average air temperature in its vicinity.

Diaphragm-operated valve 22 is closed at the beginning of the timed interval, however gas from pipe line 17 flows to pneumatic temperature transmitter 30 through non-return valve 31 and pressure regulator 32. The regulator serves to reduce the pressure of this gas before entering the transmitter from about 100 p.s.i.g. to about 20 p.s.i.g.

Diaphragm-operated valve 23 is open at the beginning of the timed interval, and the output pressure signal from temperature transmitter 30 therefore passes from pipe line 33 to temperature compensating device 34 and pneumatic temperature controller 35. (The temperature compensating device comprises an insulated reservoir, its function being to compensate for externally induced irregularities in the pressure of gas flowing through pipe line 33.) This output pressure signal is continuously indicative of the sensed average air temperature near the floor of the chamber and gradually approaches a terminal value as this air temperature approaches the average initial post-storage temperature of the cargo.

As mentioned, diaphragm-operated valves 22 and 23 are opened and closed respectively at the end of the timed interval. At this stage, temperature transmitter 30 ceases to supply temperature controller 35 with a pressure signal, but the latter is now brought into action by gas flowing through valve 22.

A temperature-sensing element 36 is mounted near the roof of the storage chamber and is of the same type as previously described element 29. This element is adapted to supply temperature controller 35 with a pressure signal continuously indicative of the average air temperature near the roof.

Comparator means (not shown) are provided in the temperature controller for comparing the terminal value of the sensed temperature near the floor with the prevailing value of the sensed temperature near the roof, and—if the latter exceeds the former—an output pressure signal of about 20 p.s.i.g. is passed from the temperature controller to selector valve 37.

Depending on the setting of this valve, the output signal serves to actuate (a) heat exchanger refrigeration means 38, or (b) heat exchanger means 38 and direct spray cooling means 39. When the difference between the two temperatures is reduced to zero, the output signal from the temperature controller is cut off and refrigeration ceases. When the sensed temperature near the roof again exceeds the terminal value of the sensed temperature near the floor, an output signal is again transmitted from the temperature controller and refrigeration is recommenced.

Refrigeration

Heat exchanger refrigeration means 38 communicates

continuously by pipe line 13 with the refrigerant supply vessel 1.

Means are provided for effecting communication as desired between the downstream side of the heat exchanger and (i) the external atmosphere or (ii) the atmosphere within the storage chamber. In the former case, the consequence of communication is refrigeration by indirect cooling (heat exchanger cooling) and discharge of vapourized carbon dioxide to the external atmosphere; in the latter case, the consequence of communication is refrigeration by indirect cooling (heat exchanger cooling) and also refrigeration by direct cooling (spray cooling), there now being discharge of vapourized carbon dioxide into the chamber.

Discharge to the external atmosphere is effected via pipe lines 40, 41, and is controlled by diaphragm-operated valve 42. The diaphragm of the latter is linked to selector valve 37 by pipe line 43. As shown in the drawing, the selector valve is set in such a way that a pressure signal from the temperature controller 35 can be transmitted by this pipe line to the diaphragm, thereby opening valve 42 and enabling discharge of vapourized carbon dioxide to the external atmosphere. The sustained passage of vapourizing carbon dioxide through the heat exchanger effects a gradual reduction in the temperature of the storage chamber.

During periods of refrigeration, excessive pressures are liable to be generated from time to time in the heat exchanger refrigeration system, and for this reason, pipe line 40 is attached via heating coil 44 to a relief valve 45 designed to open at pressures exceeding, say, 120 p.s.i.g.

Discharge into the storage chamber is effected via pipe lines 40, 46, 47 and spray cooling means 39, and is controlled by diaphragm-operated valve 48. The diaphragm of the latter is linked to selector valve 37 by pipe line 49, and—when the selector valve is set in the alternative position to that shown in the drawing—a pressure signal can be transmitted to this diaphragm to open valve 48.

A gas reservoir 50 communicates continuously with pipe line 47 on the downstream side of valve 48. When the valve is opened therefore, vapourized carbon dioxide is released both into the pipe line and into the associated reservoir, and is discharged through the nozzles of the spray cooling means into the storage chamber.

If heat exchanger 38 is comparatively small, and if diaphragm-operated valve 48 is maintained in the open position for a prolonged period, the proportion of vapourized carbon dioxide filling the heat exchanger gradually diminishes and its place is taken by liquid carbon dioxide. As this process continues, carbon dioxide is eventually discharged as a liquid through the nozzles of the spray-cooling means; the reservoir, however, remains substantially charged with vapourized carbon dioxide.

Carbon dioxide has a triple point pressure of about 60 p.s.i.g. at about -70° F. For this reason, liquid carbon dioxide is susceptible to Dry Ice formation at the comparatively low pressure contemplated by the present embodiment.

When diaphragm-operated valve 48 is closed at the end of a discharge phase, the pressure in pipe line 47 begins to fall and there is an increasing possibility of Dry Ice precipitation within the spray cooling system. Extensive nozzle blockages would therefore be expected to occur at this stage.

It has been ascertained, however, that the reservoir can provide a source of auxiliary gas at a pressure sufficient to flush residual liquid carbon dioxide and particles of precipitated Dry Ice through the discharge nozzles. As a result, blockages do not occur.

It will be appreciated that this reservoir has a critical minimum volume which must be exceeded to enable satisfactory operation under a given set of conditions. The critical volume can readily be determined by trial and error.

In the illustrated embodiment, the spray-cooling means consists of a looped arrangement including appropriate nozzles throughout its length, and carbon dioxide is distributed from a centrally located pipe to opposed segments of the loop. By adopting this arrangement there is a much diminished possibility of refrigeration being disrupted in the entire spray cooling system by the occurrence of random nozzle blockages in a part of the system.

Termination

When the storage period is at an end, the master control valve 16 is switched off and gas pressure in pipe lines 17 and 18 is reduced to normal by venting through discharge means 51. As the pressure drops from about 100 p.s.i.g. to about 20 p.s.i.g., diaphragm-operated valve 19 is opened; and at 3 p.s.i.g diaphragm-operated valve 27 closes.

The entire system is thus returned to its original condition.

As an additional refinement, it has been found advantageous to associate pipe line 25 with a quick-release valve 52.

By arranging for this valve to open at some pressure between 20 p.s.i.g. and 3 p.s.i.g., say at 15 p.s.i.g., it can be ensured that the pressure acting on the diaphragm of valve 27 is rapidly released and that this valve is therefore rapidly closed. Consequentially, there is no likelihood that premature re-setting of the master control valve can cause the unwanted closure of valve 19.

I claim:

1. A method of maintaining pre-cooled goods during storage at substantially the average initial post-storage temperature of said goods, said method comprising: loading a storage chamber with said goods; sealing the chamber; sensing continuously a first average air temperature towards the floor of the chamber during a predetermined first period of time; sensing continuously a second average air temperature towards the roof of the chamber during a subsequent second period of time; comparing continuously during said second period of time said second sensed average air temperature with the terminal value of said first sensed average air temperature and refrigerating the chamber responsively to reduce the difference therebetween.

2. Apparatus for maintaining pre-cooled goods during storage at substantially the average initial post-storage temperature of said goods, said apparatus being adapted for installation in association with a storage chamber and comprising: a refrigerating control mechanism; first means for sensing continuously a first average air temperature towards the floor of the chamber during a predetermined first period of time and for supplying simultaneously said refrigerating control mechanism with a first temperature signal continuously indicative of said first sensed average air temperature; second means for sensing continuously a second average air temperature towards the roof of the chamber during a subsequent second period of time and for supplying simultaneously said refrigerating control mechanism with a second temperature signal continuously indicative of said second sensed average air temperature; a timing device for actuating said first temperature sensing means during said predetermined first period of time and for then actuating said second temperature sensing means; comparator means included in said refrigerating control mechanism for comparing continuously said second temperature signal with terminal value of said first temperature signal; refrigerating means connected to said comparator means for refrigerating the chamber responsively to reduce the difference between said second temperature signal and the terminal value of said first temperature signal.

3. Apparatus according to claim 2, wherein said first and second temperature sensing means are pneumatically actuated by said timing device and wherein said timing device is pneumatically operated.

4. Apparatus according to claim 3, wherein said timing

device comprises: a gas storage reservoir linked by first pipe means to a source of compressed gas; said first pipe means including a diaphragm-operated valve for controlling gas flow from said source to said reservoir; means for effecting the closure of said diaphragm-operated valve when a preselected high pressure has been attained in said reservoir, said closure means comprising second pipe means for enabling closure-effecting communication between said reservoir and the diaphragm of said diaphragm-operated valve, said second pipe means including a non-return valve openable when said preselected high pressure has been attained in said reservoir; venting means for effecting the re-opening as required of said diaphragm-operated valve, said venting means being provided in the second pipe means between said non-return valve and the diaphragm of said diaphragm-operated valve and being adapted on actuation to reduce the pressure on said diaphragm; third pipe means linking said reservoir communicatively with the actuating mechanisms of said first and second temperature sensing means; bleeding means associated with said reservoir for enabling gas to escape therefrom at a controlled rate whereby to reduce the pressure

therein from said preselected high value towards and below a preselected low value.

5 5. Apparatus according to claim 4, wherein the actuating mechanism of one said temperature sensing means is adapted to operate when the pressure in the reservoir is in excess of said preselected low value, and the actuating mechanism of the other said temperature sensing means is adapted to operate when the pressure in said reservoir is less than said preselected low value.

10 6. Apparatus according to claim 5, wherein said refrigerating means comprises direct spray cooling means, the refrigerant therefor being provided by liquid carbon dioxide.
